UNITED STATES PATENT OFFICE.

WILLIAM BELLMAN, OF HARRISBURG, PENNSYLVANIA.

DESIGN FOR AN ADVERTISING-CLOCK.

SPECIFICATION forming part of Design No. 14,090, dated July 17, 1883.

Application filed December 18, 1882. Term of patent 7 years.

To all whom it may concern:

Be it known that I, WILLIAM BELLMAN, a citizen of the United States of America, residing at Harrisburg, in the county of Dauphin and State of Pennsylvania, have invented a Design for an Advertising Business-Clock, of which the following is a specification, reference being had therein to the accompanying drawing.

10 The photograph, consisting of a single figure, fully illustrates my design.

The leading features of my design consist in forming a central receptacle for a clock, and surrounding the same with a plurality of circular sections formed with round apertures suited to receive cards or business advertisements.

15 A is the central receptacle, shown in the accompanying photograph as supplied with a clock. About this receptacle are formed the circular card-receptacles B, substantially as shown, and in the position and substantially as shown is formed the circular card-receptacle C. In the material remaining between this card-receptacle C and the adjacent card-receptacles is formed the perforation *a*, to serve 20 as a hanging means. Between the card-recep-

tacles B, radiating from the central receptacle, A, are formed or otherwise affixed raised strips of any desired design. The frame or case may be made of wood or metal, the essential features as hereinbefore set forth being preserved in either case.

I claim—

1. The design for an advertising frame here- 35 in shown and described, the same consisting of the central receptacle, A, a plurality of circular card-receptacles, B, and the circular card-receptacle C, substantially as described.

2. The design for an advertising frame here- 40 in shown and described, the same consisting of the central receptacle, A, a plurality of circular card-receptacles, B, provided with intermediate raised strips radiating from the central receptacle, and the card-receptacle C, 45 substantially as described.

In testimony whereof I affix my signature, in presence of two witnesses, this 16th day of November, 1882.

WILLIAM BELLMAN.

Witnesses:

PETER STUCKER,
GEORGE HINCKEL.
